HAIR CURLER

Alexis Zachary, New York, N. Y.

Application June 2, 1950, Serial No. 165,715

7 Claims. (Cl. 132—33)

1

I have invented an improved hair curling implement for use in permanent waving, especially a hair curling implement intended chiefly to produce ringlets in the hair of women.

It is an object of this invention to provide a hair curler comprising a rotatable member which gives the hair the desired form, and a base upon which the ringlets are disposed; the member being detachable so that it can be taken off to finish the treatment. The process is terminated without said member; and the operator is thus enabled to work more quickly, effectively and to better advantage, with increased comfort and convenience to the patron.

A further object of this invention is to provide a curler adapted to facilitate the formation of ringlets in the hair, and the drying of the curls quickly, with a great saving of time and labor in the process.

The nature of the invention is made clear in the following description, taken with the drawings, illustrating the preferred forms which the invention may assume, and the novel characteristics are defined in the claims. But the disclosure is for purposes of explanation only, and various minor alterations may be made without material change in the general construction.

The device of this invention includes in general a forked base, a hair-winding member rotatable on the base, and a clamping element on the member to secure a wisp of hair in place on the implement. The member with the clamping element is easily dismounted when the hair is ready for washing and drying.

On the drawings:

Fig. 1 is a longitudinal sectional view of the member, which includes a shaft and handle to turn it.

Figure 2 is the same longitudinal section with the parts in different position.

Figure 3 is a similar section in another plane.

Figure 4 is a top plan view of the implement.

Figure 5 is a side elevation thereof.

Figures 6 and 7 are side and top views of the base.

Figure 8 shows the base and shaft in part with the hair wound on the shaft for curling, this view being a section on line 8—8 of Figure 7.

Figure 9 shows the base with the winding or curling member removed and the curled hair clamped on the base.

Figure 10 is a plan view of the base with its parts distended.

Figure 11 is a cross-section view of the gripping member of the base, enlarged.

2

Figure 12 is a longitudinal section of a curler of modified construction, and

Figure 13 is a sectional detail of a further modification.

5 The curling implement comprises a base having a body 1 with parallel projections 2 extending from one end, making the base yoke-shaped. Adjacent to the opposite end the base has a large round aperture 3 in its upper face, said aperture being also in the bottom, but reduced in diameter by an internal annular rim 3a.

Pivotedly attached to the base 1 is a hollow member comprising a tubular shaft 4 with one end for the aperture or bearing recess 3. On 15 this shaft is a slidable sleeve 5 to serve as a handle. Pivotedly united to the inner end of this handle 5 is a yoke-shaped arm 6 mounted on a pivot pin 7. This arm or element 6 clamps the end of the wisp of hair, which is wound on the arm 6 and shaft 4, as shown in Figure 8. The arm 6 is lifted and the end of the wisp is laid against the tube 4. The arm 6 is then turned down to grip the hair, and the shaft is turned to wrap the hair on the tube 4 and arm 6 together. The clamping arm 6 lies closely against the tube and has a curved form to fit the exterior surface thereof. When in use, the base 1 rests against the patron's head and the hair encircles the shaft 4 in a spiral.

20 In the sides of the tubular shaft 4 are slots 8 through which the pin or stud 7 passes. These slots 8 are long enough to permit movement of the handle from the position shown in Figure 1 to the middle of the shaft 4, as illustrated in Figure 2; so that the free end of the clamping element 6 may be close to the base 1. Inside the tubular shaft 4, at the end to be connected to the base 1 is an inverted U-shaped spring 9 fixed in place by a rivet 10. The ends of this spring are bent outward as indicated at 11, and can be urged to project through apertures or slots 12 in the sides of the shaft 4 at the end. Ordinarily the ends 12 are retracted by compression springs 13 in the shaft 4 which bear against the springs 9.

25 The middle of the spring 9 has an aperture 14, and within the tube 4 about at the middle is a link 15 with its top and bottom ends closed, and two of its sides 16 closed. In the other two sides are slots 17 through which extends the pin 7. This link is connected by a rod 18 to a cam block 19 within the spring 9. Obviously when the handle forces the arm 6 down to the base, the pin engages the link 15 and impels the block 19 down between the parts of the spring 9 which lie close together, and spreads these parts, caus-

ing the outturned ends 11 to protrude through the slots 12. The two arms of the spring 9 normally incline towards each other at the ends 11.

The legs or projections 2 of the base are hollow, and at the junction thereof are two flat superposed extensions 20, that project away from the legs and are separated from one another over their entire lengths. The large hole 3 is in the upper extension and the smaller hole with the rim 3a is in the lower. The base also comprises a part or member 21 that is also yoke-shaped or concave at one end, with internal ribs 22 along the sides 23. The member 21 is movably joined to the base by a strip of elastic 24, the ends of which are affixed in the outer extremities of the hollow projections 2. This strip passes through both sides 23, which are hollow to receive it; and these arms are further beveled as indicated at 24 on the face of the base which rests against the head bearing the hair under treatment.

To employ the device, the base is laid against the head, and the shaft 4 joined to the base 1. This is done by inserting the lower end of the shaft into the aperture 3, and sliding the handle 5 forward till the pin 7 moves the link from the position shown in Figure 1 to the position shown in Figure 2. The block 19 thus moves farther in between the arms of spring 9. The ends 11 of the springs are thus forced through the slots 12, and the base 1 and shaft 4 are rotatably connected so that the shaft can turn in the base 1. The device can thus readily be handled as a unit and put upon the patron's head at the selected point. Of course the required number of these units will be utilized to engage the hair wherever the treatment is to be given. When the end of the shaft is in the base it rests on the rim 3a, and the ends 11 engage partly with the undercut edge 26 at the junction of the projections 2, and partly under the edge of the opening 3 in the top extension 20.

The arm 6 is then lifted, and the operator lays the skein or wisp of hair 27 against the shaft 4 and clamps it under the arm. The shaft 4 is now turned to wind the hair on the shaft and element 6 together. The shaft 4 is first given a coating of the setting solution, and the hair 27 is held till the spiral assumes its permanent form.

When the shaft 4 is rotated with respect to the base, the projecting ends 11 of the spring or retaining means 9 of course move around inside the base and the shaft 4 is held in place as it turns, and the ends 11 prevent separation of the shaft and handle from the base. The arms of the spring 9, while shown as two in number, can be increased to four if necessary.

The spiral curls 27 when set are pressed down on the shaft towards the base 1 and engaged by the element 21. First the clamping element 21 is pulled out from the base, raised and slipped upon the shaft 4. The shaft fills the recess or concave end between the arms 23. The shaft 4, if desired, can now be detached by pulling it out of the aperture 3. The treatment is finished by washing the hair and drying with only the base 1 and clip or element 21 in place. After drying, the base 1 and element 20 are removed, and the turns in the hair 27 separate and spread out, but the curves remain.

The diameter of the curls can be increased by attaching a plate 28 to the arm 6. This plate conforms to the shape of the arm, and is put on by slipping a rivet 29, which it carries, into a slot 30 which has its open end in the pivoted end of

the arm 6. A spring 31 in the handle 5 engages the shaft 4 and keeps the parts in tight fit.

The curler of Figure 12 has a tubular shaft 4 with a tube 32 therein fixed at both ends. In this shaft are springs 9' with ends 11 to project as before through apertures 12 in the forward end of the shaft. A cam block 19 for this spring is joined to a rod 33 which projects through the opposite end of the shaft and carries on its outer end a knob 34. The opposite end of the shaft 4 carries an elongated cap 35, and a sleeve 36 on the shaft 4 carries the clamping arm 6. This sleeve is slidable on the shaft and one end can be inserted into the cap 35. Inside the shaft 4 and around the tube 32 is a spring 37, seating against the cap 35, which closes the end of the shaft; and a ring 38 surrounding the tube 32. The sleeve 36 is connected to the ring 38 by pins or studs 39, slidable in slots 8 in the sides of the shaft 4. Hence the sleeve, serving as a handle can be moved against the spring 37 to pull the clamping arm 6 away from the base 1 when the shaft is to be detached.

In Figure 13, the knob 34 is shown with rods or pins 40 attached and extending into a sleeve 41 which envelops the cap 35 and is made fast to said cap. The pins 40 are long enough to project from the opposite end of the cap 35 and the sleeve 41. On the sleeve 36 near the upper end is a collar 42. When the sleeve 36 is moved to retract the clamping arm 6, it strikes the pins 41 and retracts the cam block 19 also. The pin or screw securing the sleeve 41 to the cap 35 is indicated at 44. The sleeve 41 can be omitted if desired, and the pins 40 placed inside the cap 35. The hollow shaft 4 with the springs therein in the implement shown in Figure 13 is the same as the form indicated at the lower half of Figure 12.

In Figure 1 the shaft 4 is shown with a coiled spring 45 in its upper end to engage the link 7 and urge it to carry the block 19 between the arms of the spring 9.

The invention of this case is similar to the curlers of my copending applications, Serial Nos. 43,491 and 52,817 now Patent Nos. 2,590,669 and 2,585,611 respectively; but the claims herein are drawn to the combination of the base with the movable part 21 and the means carried by the shaft 4 to operate the springs 9', such means being the movable handle 5; and the rod with the knob 34, passing through the shaft 4 as in Figures 12 and 13.

Having described my invention, what I claim as new is:

1. A hair curler comprising a flat base with projections extending therefrom at each side, the base having a bearing aperture adjacent the junction of the projections, a hollow shaft having one end in said aperture, retaining means in one end of the shaft to engage the edges of said aperture to hold said shaft on said base, a handle slidably mounted on the shaft and connections in the shaft operable by said handle, to actuate said retaining means.

2. A hair curler comprising a base with projections extending therefrom at each side, the base having a bearing aperture adjacent the junction of the projections, a hollow shaft having one end in said aperture, resilient retaining means in one end of the shaft to engage the edges of said aperture to hold said shaft on said base, and means carried by the shaft and movable longitudinally thereof to operate said retaining means, said base including a bodily movable detachable clip yieldably attached to the base.

3. A hair curler comprising a flat base with projections extending therefrom at each side, the base having a bearing aperture adjacent the junction of the projections, a hollow shaft having one end in said aperture, retaining means in one end of the shaft to engage the edges of said aperture to hold said shaft on said base, a handle slidably mounted on the shaft and connections in the shaft operable by said handle, said means having the form of a bent spring with arms having outturned ends in said end of the shaft, a cam block in the shaft to engage said ends and force them to project out through openings in the shaft at said end, the connections including a slotted link in the shaft joined to said cam block and said handle.

4. A hair curler comprising a base with projections extending therefrom at each side, the base having a bearing aperture adjacent the junction of the projections, a hollow shaft having one end in said aperture, retaining means in one end of the shaft to engage the edges of said aperture to hold said shaft on said base, and means carried by the shaft to operate said retaining means, said base including a detachable clip yieldably attached to the base, said base also having extensions at the junction of said arms with a space between them, the clip having arms at the sides with ribs between said extensions, and an elastic strip with its ends fast in the projections and engaging said clip, to enable the clip to be retracted from the remainder of the base.

5. A hair curler comprising a flat base with projections extending therefrom at each side, the base having a bearing aperture adjacent the junction of the projections, a hollow shaft having one end in said aperture, retaining means in one end of the shaft to engage the edges of said aperture to hold said shaft on said base, a handle slidably mounted on the shaft and connections in the shaft operable by said handle, said means having the form of a bent spring with arms having outturned ends in said end of the shaft, a cam block in the shaft to engage said ends and force them to project out through openings in the shaft at said end, the connections including a slotted link in the shaft joined to said cam block and said handle, said base also having extensions at the junction of said arms with a space between them, the clip having arms at the sides with ribs

between said extensions, and an elastic strip with its ends fast in the projections and engaging said clip, to enable the clip to be retracted from the remainder of the base.

5 6. A hair curler comprising a base having a bearing aperture therein, a hollow shaft for insertion at one end into the aperture, a tube in the shaft, retaining means in the one end of the shaft, said means having out-turned ends, and means carried by the shaft and extending through the tube for actuating said out-turned ends through openings in the shaft to engage under the rim of the aperture, to couple the shaft rotatably to the base, said means comprising a cam block on said means, a rod joined to the block extending at the opposite end outside of the shaft, and a knob on the outer end of said rod, a cap fixed on the opposite end of the shaft, a sleeve slidably mounted on the shaft, and a clamping arm on the last-named sleeve, one end of the sleeve being insertible into the cap.

10 7. A hair curler comprising a base having a bearing aperture therein, a hollow shaft for insertion at one end into the aperture, a tube in the shaft, retaining means in the one end of the shaft, said means having out-turned ends, and means carried by the shaft and extending through the tube for actuating said out-turned ends through openings in the shaft to engage under the rim of the aperture, to couple the shaft rotatably to the base, said means comprising a cam block on said means, a rod joined to the block extending at the opposite end outside of the shaft, and a knob on the outer end of said rod, a cap fixed on the opposite end of the shaft, a sleeve fixed to the cap, a sleeve slidably mounted on the shaft, and a clamping arm on the last-named sleeve, one said knob having rods extending through the first-named sleeve, and said last-named sleeve having a collar adjacent end to engage said rods.
